CART FOR A TELEVISION RECEIVER

James W. Kelso, Pacific Palisades, Calif., assignor to Packard-Bell Electronics Corporation, Los Angeles,
Calif., a corporation of California

Filed Apr. 2, 1963, Ser. No. 74,256

Term of patent 14 years

(Cl. D33—14)

The broken line showing of a television receiver in FIGURE 1 is for illustrative purposes only.

I claim:

The ornamental design for a cart for a television receiver, as shown and described.
